UNITED STATES PATENT OFFICE.

NICHOLAS CARMAN, OF SPRINGFIELD, OHIO.

DESIGN FOR A BADGE.

SPECIFICATION forming part of Design No. 17,678, dated September 6, 1887.

Application filed May 10, 1887. Serial No. 237,772. Term of patent 3½ years.

To all whom it may concern:

Be it known that I, NICHOLAS CARMAN, a citizen of the United States, and a resident of Springfield, in the county of Clark and State of Ohio, have invented and produced a new and original Design for Badges, of which the following is a specification, reference being had to the accompanying drawings, forming a part thereof.

10 Figure 1 is a view looking at the face of my newly-designed badge, and Fig. 2 a like view showing a slight modification thereof.

The design consists of a ring or circular band, A, the face whereof is suitably ornamented, 15 as seen in the figures. At about equidistant points round the periphery of said band are secured thereon or extend therefrom three plates, B, constituting each a part of a triangle. The face of these plates, near the 20 edge, is ornamented by some suitable border. Extending from plate to plate are portions of a wreath, while projecting from the outer edges of the lower plates are the hilts of two swords and a short portion of the blades, 25 the points of the respective swords presenting themselves to view at diametrical points from the hilts and projecting from the band A across the upper portions of the wreath. Extending from the lower part of the said band and across 30 the adjacent portion of the wreath is another sword-hilt, with a short piece of the blade also appearing. Superimposed upon the upper plate is the representation, C, of the upper part of an armor or mail, with a helmet, D, and a 35 visor, E, thereon, while surmounting the whole and standing upon the helmet is a figure of an eagle with its wings somewhat outspread. So far the principal design and the modification are alike. Within the band A is a plate,

F, substantially of triangular form, there being 40 a jog in two sides thereof near the upper end. This plate is ornamented by a suitable border, and upon it is inscribed the figure of a lily.

Referring now to the modification shown in Fig. 2, there is a similar triangular plate, F', 45 with an ornamental border, and having inscribed thereon a representation of a skeleton-head with crossed bones beneath it in one corner, and in the opposite corner is the representation of a book resting upon a pedestal, 50 and two swords laid across the book, while near the lower corner there is a larger book in an open position, with a sword lying upon it.

The principal features of my design are the partial triangular plates, the band connecting 55 them together, and the triangular plate within the band.

I claim—

1. The design of a badge herein shown and described, the same consisting of the ornamented band A, the triangular plate F within it and having a figure or figures thereon, as shown, and of the partially-triangular plates B.

2. The design of a badge herein shown and described, the same consisting of the circular 65 ornamented band A, the triangular plate F, having a lily represented thereon, the partially-triangular plates B, the armor C, the helmet D, the visor E, the eagle on the helmet, the portions of the wreath between the plates, 70 and the crossed swords.

In testimony whereof I affix my signature in presence of two witnesses.

NICHOLAS CARMAN.
